UNITED STATES PATENT OFFICE

JOSEPH P. MUZZIO, OF CLEVELAND, OHIO, ASSIGNOR TO THE FOUR-WAY LOCK COMPANY, OF CLEVELAND, OHIO, A CORPORATION OF OHIO

HASP

Application filed May 14, 1928. Serial No. 277,575.

This invention relates to hasps, such as are used with a padlock for locking doors, cupboards and the like.

The invention relates particularly to that form of hasp where the swinging plate is swung into position over the lock-receiving staple, usually concealing the securing screws for both hasp and staple, to prevent detachment of the hasp without opening the lock. Such hasps usually are provided with a hinge pin and the purpose of the lock and hasp is sometimes defeated by cutting or filing off one of the heads of the hinge pin, pushing out the pin and later restoring it so that the fact that access has been had is concealed.

The present invention has for its object to provide a hasp that does away with hinge pins and forms the hinge connections from the plates themselves, and in such manner that access to the cupboard or other place cannot be obtained without leaving noticeable traces on the hasp, and moreover, a hasp of this kind whose hinge parts are offset so that no deformation of the surface is necessary for attachment.

In the drawings, which represent one suitable embodiment of the invention, Fig. 1 is an elevation with the hasp open; Fig. 2 is a similar elevation with the hasp closed; Fig. 3 is an end elevation of the hinge end of the hasp base; Fig. 4 is a similar view of the hinge end of the hasp plate; and Fig. 5 is a sectional plan view on the line 5-5, Fig. 2.

While the hasp is suitable for use in any place where two parts are to be locked together or released, such as a door to its casing or the like, the drawings for convenience show the invention applied to two adjacent garage doors 1, 2, both of which may be assumed to swing. The hasp set includes two members which are respectively attached to the two doors or other parts. The first is the staple member, which includes a suitable base plate 3 carrying the staple 4, which is of loop form with its ends passing through openings in an embossed portion 5 of the plate and headed over or upset beneath the same to avoid projections beyond the rear surface of the plate, which may therefore be attached

directly to the flat surface of the door by any securing means, such as the bolts or screws 6.

The second member is the hasp, which likewise includes a base or body plate 7 attached to the other door member 1 in any suitable manner, such as by the bolts or screws 8, and to one end of which is pivotally connected the hasp plate 9. The hinge connection is at the opposite edge of the base plate 7 from the staple plate 3, so that when the hasp is swung over to locked position with its recess 10 slipped over the staple 4, said plate covers and prevents access to the securing devices, 6, 8 of both plates, as is usual.

The hinge connection between the hasp plate 9 and its base plate 7 is formed of the metal of said plates, by lacing them together as it were, thereby avoiding use of any hinge pin. Moreover, the end edge portions of the two plates are offset or bent outwardly from the planes of the plates, as shown more particularly in Fig. 5. As a result, the hinge connection produces no projection of the parts beyond the rear surface of the base plate 7 and it may be attached directly to the flat surface of a door without forming a recess to receive the hinge connection. One of the parts 7 or 9 is formed with end extensions 11, two being shown, beyond its offset edge portion 12, the extensions being rolled to form eyes, with the turns of said eyes passing through recesses 13 in the offset portion of the base plate 7. The arrangement is such that the metal of each eye is rolled back upon itself practically into abutting relation with the offset plate portion 12, as indicated at 14, Fig. 5, so that in closed position of the hasp the free end edge of each loop is contained within the recess in the base plate 7.

It is therefore protected against any access thereto of a splitting or prying tool, such as a chisel or screwdriver. In the swinging motion of the hasp, of course, it turns freely upon the metal bridges 15 of plate 7 opposite each of the recesses therein, which bridges therefore serve as the hinge pin.

With this hasp it is impossible to take off the hasp plate without severing the eyes 11 or cutting through the bridges 15, either of which operations is at best a difficult task and

inevitably leaves noticeable traces of its occurrence.

What I claim is:

A hasp of the character described, comprising a base plate adapted for application of one of its faces to a supporting surface and at one end having laterally slotted and offset angularly away from said face to form a hinge bridge spaced therefrom, and a staple 10 receiving plate having one end correspondingly offset and bent into eye form embracing said hinge bridge, the free end of said eye entering said slot on the same side of the base plate as its said surface, whereby in 15 locked position of the hasp the free end of said eye is concealed and inaccessible beneath the offset ends of said plates.

In testimony whereof I hereby affix my signature.

CERTIFICATE OF CORRECTION.

Patent No. 1,799,861.

Granted April 7, 1931, to

JOSEPH P. MUZZIO.

It is hereby certified that error appears in the printed specification of the above numbered patent requiring correction as follows: Page 2, line 7, the claim, for the word "having" read being; and that the said Letters Patent should be read with this correction therein that the same may conform to the record of the case in the Patent Office.

Signed and sealed this 28th day of April, A. D. 1931.

**M. J. Moore,
Acting Commissioner of Patents.**
